by Walter S. Lombard,
Atty.*

UNITED STATES PATENT OFFICE.

JOHN WILLIAM AULSON, OF LYNN, MASSACHUSETTS.

LEATHER-GRAINING MACHINE.

Application filed May 18, 1923. Serial No. 639,828.

To all whom it may concern:

Be it known that I, JOHN W. AULSON, a citizen of the United States of America, and a resident of Lynn, in the county of Essex 5 and State of Massachusetts, have invented certain new and useful Improvements in Leather-Graining Machines, of which the following is a specification.

This invention relates to hide working 10 machines and particularly to machines of this character which are used to grain, board, or soften hides and skins after they have been tanned.

The object of the invention is the production of a simple but effective power-driven machine which will operate on the hides or skins in substantially the same manner as when a manually actuated board is rubbed over the surface of the hide or 20 skin.

The invention consists primarily of a support for the hide or skin and having a drum coacting therewith, which is adapted to reciprocate over said bed and oscillate 25 during its reciprocation.

The invention further consists in certain novel features of construction and arrangement of parts which will be understood readily by reference to the description of 30 the drawings and to the claims to be hereinafter given.

For the purpose of illustrating the invention, one preferred form thereof is illustrated in the drawings, this form having 35 been found to give satisfactory and reliable results, although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents a plan of a machine embodying the principles of the present invention.

Figure 2 represents a side elevation of the same, and

Figure 3 represents a transverse section of the drum.

Similar characters indicate like parts throughout the several figures of the drawings.

In the drawings, 10 is a framework having side bars 11 extending lengthwise

thereof and two pairs of guide members 12 parallel to the bars 11, each pair of guide members being spaced apart.

Between the side guides 12 on opposite sides of framework 10 are disposed blocks 13 adapted to be reciprocated between said guides.

In the blocks 13 is revolvably mounted a shaft 14 having a drum secured thereto, 65 said drum consisting of the separated cylindrical end disks 15 and the semi-cylindrical member 16, the opposite ends of which are secured to the disks 15. The member 16 acts as a "board" such as is 70 ordinarily used in machines of this class.

The periphery of this semi-cylindrical member 16 has glued or otherwise secured thereto a sheet 17 of material, the outer surface of which is adapted to grip a hide. 75

To the under side of both side bars 11 are secured the racks 18, the teeth of each of which mesh with a gear 19 secured to an outer end of the shaft 14.

At the rear end of the frame 10 are bearings 20 in which is revolvably mounted a drive shaft 21 having a driving pulley 22 secured thereto, and by which rotary movement may be imparted to said shaft 21.

On the opposite ends of the shaft 21 are secured fly wheels 23, each fly wheel having pivotally connected thereto at 24 one end of a connecting rod 25, the opposite end of which has an opening 26 therein through which the outer ends of the shaft 14 extend. 90

When the shaft 21 is rotated by means of a belt (not shown) on the driving pulley 22, the blocks 13 will be reciprocated between the side guides 12. During this reciprocation, owing to the meshing of the 95 teeth of the gears 19 with the teeth of the racks 18, an oscillating movement will be imparted to the drum 15, 16.

On the lower face of the side bars 27 are secured bearings 28 in which is mounted 100 an oscillating shaft 29 having the treadle arms 30 secured thereto, the front end of these arms 30 having a foot board 31 mounted thereon.

To each treadle arm 30 is pivotally secured at 32, a T-shaped member 33, this member being articulated at 34, 34 to one end of each of two levers 35 pivoted at 36, 36 to a side bar 27.

The opposite ends of these levers 35 are 110 pivotally connected at 37 to the adjustable members 38, the upper ends of which are

pivottally connected at 39 to the hide support table 40 adapted to be moved vertically between the plates 41 at the front and rear ends of said hide support 40.

5 This hide support 40 has at the top thereof a forward extension 42 by means of which the hide may be positioned upon the support more readily.

On the upper surface of this hide support 40 is glued or otherwise secured a sheet 10 of material 43, the upper surface of which is adapted to grip the hide placed thereon.

Normally the hide support 40 is in the position indicated in Fig. 2 of the drawings, 15 and when the drum 15, 16 is at or near the rear end of the frame 10, the operator places a folded hide upon the gripping sheet 43, the fold or bight of the hide being toward the rear of the machine.

20 When the drum reaches its forward position, the operator presses upon the foot board 31, moving the treadle arms 30 about the pivot 29, and thus forces the hide support with the folded hide thereon upwardly 25 against the drum 15, 16, in which position the hide support is retained until the drum in its reciprocation reaches its rearmost position.

As the drum commences to oscillate during 30 the rear movement of the drum, the hide-gripping sheet 17 thereon will grip upon the adjacent face of the hide and cause it to be moved toward the rear of the machine, the lower layer of the hide being 35 retained in position on the sheet 43 by the friction thereof. As a consequence of this movement, the bight or fold of the hide will be moved toward the rear of the machine until the drum reaches its extreme 40 rearward position.

The operator then removes his foot from the foot board 31 of treadle 30 and the hide support 40 will return, of its own weight, to its normal position.

45 The operator then seizes the hide and turns it over upon the support 40 and repeats the operation so that the other half of the hide will be treated in the same manner.

50 By pinching the bight or fold of the hide in this manner a grain will be formed all over the finished side of the hide.

If it is desired to produce a box effect upon the finish side of the hide, the hide 55 will be folded again so that the fold will be at right angles to the fold previously described, and the two operations just mentioned will be repeated.

When a pebbled or fancy effect is preferred, the operations of the hide may be carried still further with the hide folded 60 at an angle to the folds hereinbefore referred to.

It must be understood that when the hide 65 is folded, the finish faces are always inside.

It is obvious therefore that by means of this machine any design may be given to the finish faces of the hide that could be secured by hand operation and with less labor and in less time.

70 It is believed that the operation and many advantages of the invention will be understood readily without further description.

Having thus described my invention, I 75

1. In a machine of the class described, a hide support; guides parallel to said support; a drum reciprocable on said guides; means for oscillating the drum during its reciprocation, and treadle mechanism for 80 bodily lifting said hide support and retaining it in parallelism with said guides.

2. In a machine of the class described, a hide support; guides parallel to said support; a shaft to which said drum is secured; a gear secured to said shaft; means coacting with said gear for oscillating the drum during its reciprocation for bodily lifting said 85 hide support and retaining it in parallelism 90 with said guides.

3. In a machine of the class described, a hide support; a sheet of hide-gripping material on said support; guides parallel to 95 said support; a drum reciprocable on said guides; means for positively oscillating the drum during its reciprocation; adjustable members depending from opposite ends of said hide support; a treadle; and means interposed between said treadle and said 100 adjustable members adapted to move said members an equal distance during each movement of the treadle.

4. In a machine of the class described, a hide support; guides parallel to said support; a drum reciprocable on said guides; means for oscillating the drum during its reciprocation; members depending from 105 said hide support; pivoted levers articulated at one end to the lower ends of said depending members; pivots for said levers intermediate their ends; a member connecting the opposite ends of said levers; and a treadle to which said connecting member is pivoted at a point removed from the 110 pivot of said treadle.

5. In a machine of the class described, a hide support; a sheet of hide-gripping material on said support; guides parallel to 115 said support; a drum reciprocable on said guides; means for oscillating the drum during its reciprocation; members depending from said hide support; levers mounted on pivots midway of their length with their outer ends articulated to said depending members; a member interposed between the adjacent ends of said levers and pivotally connected thereto; and a treadle pivotally connected at a point intermediate its length 120 to said lever connecting member.

6. In a machine of the class described, a frame; a hide support adapted to be moved vertically; a treadle; connections between said support and treadle; guides parallel to said support; a drum reciprocable on said guides; means for oscillating the drum during its reciprocation; plates upon said frame against which the opposite ends of said hide support in its vertical movement are adapted thereby imparting oscillatory movement to the drum during its reciprocation. 55
- 5 to said support; a drum reciprocable on said guides; means for oscillating the drum during its reciprocation; plates upon said frame against which the opposite ends of said hide support in its vertical movement are adapted 10 to contact; and means for imparting vertical movement to said hide support and retaining it in parallelism with said guides.
7. In a machine of the class described, a frame; a hide support; a treadle; guides parallel with said support; a drum reciprocable on said guides; means for oscillating the drum during its reciprocation; vertical bearing plates on said frame coacting with the opposite ends of said hide support to 15 prevent lateral movement thereof; adjustable members depending from said hide support; horizontally disposed levers pivoted midway of their length to said frame with their outer ends pivotally connected to the lower ends of said depending members; and a T-shaped member connecting the inner ends of said levers and pivoted to said 20 treadle.
8. In a machine of the class described, a frame having side bars and guides; a hide support movable vertically in said frame; blocks adapted to be reciprocated with their upper and lower faces in contact with the opposed faces of said guides; means for reciprocating said blocks; an oscillating shaft mounted in bearings in said blocks; a drum secured to said shaft; gears secured to said shaft and movable therewith; and racks on 25 said bars engaging the teeth of said gears thereby imparting oscillatory movement to the drum during its reciprocation. 30
9. In a machine of the class described, a frame having side bars and guides; a hide support movable vertically in said frame, the upper face of said support having a sheet of gripping material secured thereto; blocks adapted to be reciprocated with their upper and lower faces in contact with the opposed faces of said guides; means for reciprocating said blocks; an oscillating shaft mounted in bearings in said blocks; a drum secured to said shaft; gears secured to said shaft and movable therewith; and racks on 35 said bars engaging the teeth of said gears thereby imparting oscillatory movement to the drum during its reciprocation. 40
10. In a machine of the class described, a frame having side bars and guides; a hide support movable vertically in said frame; means for imparting vertical movement to said support and retaining it horizontal during such movement; blocks adapted to be reciprocated with their upper and lower faces in contact with the opposed faces of said guides; means for reciprocating said blocks; an oscillating shaft mounted in bearings in said blocks; an oscillating shaft mounted in bearings in said blocks; a drum secured to said shaft and movable therewith; gears secured to said shaft and movable therewith; and racks on 45 said bars engaging the teeth of said gears thereby imparting oscillatory movement to the drum during its reciprocation. 50
11. In a machine of the class described, a frame having a pair of parallel guides at each side thereof; a block adapted to be reciprocated between each pair of guides; crank mechanism for reciprocating said blocks; an oscillating shaft mounted in bearings in said blocks; a drum secured to said shaft and movable therewith; gears secured to the outer ends of said shafts; fixed racks meshing with said gears to impart oscillatory movement to said shaft and drum during the reciprocation; and a hide support horizontally disposed beneath said drum and having on its upper face a sheet of material adapted to grip the hide while being operated upon. 55
12. In a machine of the class described, a frame having parallel guides at each side thereof; a block adapted to be reciprocated between each pair of guides; an oscillating shaft mounted in bearings in said blocks; a drum secured and movable with said shaft; gears secured to the outer ends of said shaft; fixed racks meshing with the teeth of said gears to impart an oscillatory movement to said drum during the reciprocation of said blocks; a hide support; a hide-gripping material secured to the upper face thereof; and means for raising said hide support a predetermined distance. 60
